UNITED STATES PATENT OFFICE.

WELLING G. TITUS, OF TRENTON, NEW JERSEY.

DESIGN FOR A STEIN OR MUG.

No. 39,957.

Specification for Design.

Patented May 4, 1909.

Application filed February 18, 1909. Serial No. 478,744. Term of patent 3½ years.

To all whom it may concern:

Be it known that I, WELLING G. TITUS, a citizen of the United States, residing at Trenton, in the county of Mercer and State of New Jersey, have invented a new, original, and ornamental Design for Steins or Mugs, of which the following is a specification, reference being had to the accompanying drawings, forming part thereof.

Figure 1, is a view in elevation of a stein or mug showing my new design. Fig. 2, is a

perspective view of the stein or mug taken from the opposite side from that shown in Fig. 1.

I claim:

The ornamental design for a stein or mug as shown.

WELLING G. TITUS.
